TEXTILE WASHING AND DRYING
APPARATUS

John W. Chamberlin, Mequon, Wis., assignor, by
mesne assignments, to Aveo Manufacturing
Corporation, New York, N. Y., a corporation
of Delaware

Application May 31, 1946, Serial No. 673,515

4 Claims. (Cl. 68—20)

1

This invention relates to an automatic machine for washing and drying of textiles.

It is a primary object of the present invention to provide a mechanism for effectively accomplishing both washing and drying in a single machine with a minimum of mechanism and by using certain of said mechanisms for performing functions in both washing and drying.

It is another object to provide means in a combined washer and dryer for effectively sealing portions of the dryer mechanism during the washing operation and to automatically open said sealed portions when the machine is operated as a dryer.

It is a further object to provide a combined washer and dryer mechanism in which the drain assembly employed for removing wash water is also used to drain condensed moisture from the machine during the time the machine is used as a dryer.

The above and other objects of the invention will appear more fully from the following more detailed description and by reference to the accompanying drawings forming a part hereof and wherein:

Figure 1 is a cross section through a machine showing the clothes cylinder tub and a portion of the drying mechanism.

Figure 2 is a section taken on the lines A—A of Figure 1 showing a section through the machine and a plane at right angles to the plane of Figure 1.

Figure 3 is a view and section on the line B—B of Figure 1.

Figure 4 is a top view of the machine shown in Figure 1.

Figure 5 is a diagram showing the general arrangement of the several elements and particularly the wiring diagram of the several electrical units.

Referring to the drawings, the cylindrical shaped tub 10 has a clothes containing cylinder 11 mounted for rotation therein, the clothes cylinder being of the type which is mounted for rotation on a substantially horizontal axis on a shaft 12. The shaft 12 is mounted on one end of the cylinder which is driven for rotation from a drive motor 13 through a belt 14 and a gear box 15 thus providing two speeds of rotation for the cylinder 11, one speed for washing and a higher speed for centrifugal extraction. The washing or tumbling speed of rotation is provided through the gear box 15, a higher gear ratio being made available by actuation of a clutch inside the gear box which clutch is con-

2

trolled by the actuation of an electrical solenoid 16. By actuation of the solenoid 16, a higher speed of rotation of the cylinder 11 is made available for extracting the washing or rinsing liquid from the clothes by centrifugal force. The opposite end of the motor 13 is provided with a second gear box 17 also affording two speeds of rotation for driving a combination blower and pump 18 the unit operating as a pump at low speed and as a blower for air at high speed. A high speed drive for operating the combined unit 18 as an air handling blower is effected by actuation of a solenoid 19 but when the solenoid is not actuated the lower speed of operation of the unit 18 is effective to actuate the unit at a speed suitable for operation as a liquid handling pump. The combined blower and pump element 18 is connected as a part of the drain for the machine at the bottom of the tub 10 through a conduit 20 and a sump 21 thus providing fluid circulating means in the drain outlet for handling both water and air. The conduit 20 is connected to the central inlet of the combined pump and blower unit and a drain conduit 30 is connected with the outlet side of the pump-blower combination.

The tub 10 is housed in an outer casing 22 as shown in Figure 1. The casing is spaced from the tub 10 a sufficient amount to allow an air heating chamber 23 to be positioned adjacent the top of the tub 10 between the tub and the top of casing 22 as shown in Figures 1 to 4 inclusive. This air heating chamber is adjacent the wall of the tub 10 and an opening is provided from the heating chamber 23 into the tub 10. This opening or passage may be opened or closed by actuation of a plurality of overlapping pivoted louvers 24 which are rectangular shaped overlapping members pivoted on their longitudinal axes and designed to be opened by the actuation of a solenoid 25 and to be closed by a spring when the solenoid 25 is not actuated. Thus by the actuation or lack of actuation of the solenoid 25 the louvers may be swung on their axes to open or close the passageway between the heating chamber 23 and the tub 10, the closed position providing a watertight seal for the opening between the heater chamber 23 and the tub 10 during washing operations. Just above the louver controlled opening 24 an electrical heating element 26 is located in the heating chamber and adjacent to and above this heating element 26 is a fan 27 with an electrical drive motor 28 above the fan. The heating chamber 23 is provided with an air inlet 29 at the top of the

cabinet or casing 22 and a soap opening 31 with suitable closure 32 is provided through the heating chamber 23. The outer surfaces of heating chamber 23 and the tub 10 are preferably covered with heat insulation material 33.

For the purpose of supplying water for washing, a water mixing valve 35 is provided which takes water from cold inlet 36 and hot inlet 37 and supplies mixed water at a temperature determined by a water temperature control member 38. Water supply valve 39 received water from the mixing valve 35 and feeds into a mixing chamber 41 which in turn supplies water into tub 10 through a conduit 42 (Figure 5).

A drain valve 45 in the conduit 20 adjacent the sump 21 may be opened by actuation of a solenoid 46 controlling such valve. A float chamber 47 (Figure 3) indicating the height of water in the tub 10 (shown in diagram Figure 5 as separate from the tub for convenience only) causes the water supply valve 39 to be shut off by opening the circuit thereto when the level of water in the tub 10 becomes a predetermined amount.

In order that the several units of the mechanism may be controlled in timed sequence to effect the desired cycle of operations in soaking, washing, rinsing, extracting and drying, a timer assembly 50 is employed which comprises a synchronous electric drive motor (not shown) which rotates a shaft 52 carrying a plurality of switch actuating cams 53, 54, 55, 56 and 57. The time for one rotation of the cams is the time necessary to complete one cycle of operation through soaking, washing, rinsing, extracting and drying. Thus the cam 53 controls a circuit which when closed causes motor 13 and the synchronous timer motor to be operated. Likewise the cam 54 will cause water to be admitted to the wash cylinder by closing the circuit to open valve 39 during a portion of the rotation of the shaft 52. The closing of this circuit will cause water to be admitted to the tub until the level is reached which will cause the float control valve 47 to open the circuit and shut off the water. The cam 55 controls the circuit to the drain valve 45 by actuating the solenoid 46. This drain valve is open for a portion of rotation. The cam 56 controls the actuation of the solenoid 16 to change the gear ratio of the gear box 15 from low speed for washing operation to high speed for centrifugal extraction.

The cam 57 is the dryer control cam and this cam provides for closing of the circuit to the heating element 26. The other units previously listed which are in the heating circuit are the fan motor 28, the louver opening solenoid 25 and control solenoid 19. The circuit for heating element 26 also has a series connection with thermostatic elements 26A and 26B located at the top of the tub 10 and in the sump 21, these elements being set to open the circuit at a temperature at which the heating element 26 is to be shut off. The actuation of solenoid 19 assures that the combination drain pump and blower unit 18 will be rotated at the high speed required for operation as a blower to draw moisture saturated air from the tub 10 through the sump 21 and into the drain line 30.

During the operation of the machine as a washer the louvers 24 are in a closed position, a spring urging the louvers to the closed position. However, when the timer dial carrying the timer cams moves cam 57 to the position for drying the solenoid 25 is actuated, as will be

evident on consideration of the diagram in Figure 5. Such actuation of solenoid 25 will open the louvers and allow air passage between the chamber 23 and the tub 10. Several units in the 5 dryer circuit are actuated at the same time by the cam 57 including the fan motor 28, the heating element 26 and the thermostats 26A, 26B, all of which are on the same circuit and actuated by the single cam operated switch adjacent cam 10 57. In addition to the fan 27 and the fan motor 28 which forces heated air into the clothes cylinder, the combined pump and blower assembly 18 is actuated for high speed by the operation of the solenoid 19 and this higher speed of rotation of the pump-blower circulating unit 18 is assured at the time the drying operation is started thus providing for the movement of moisture saturated air into the drain line 30. The moisture in this air will be condensed either in the 20 atmosphere or into any outlet which may be provided. It is evident that major air circulation will be over the heating element adjacent the tub and that the inlet of air into the inlet 29 will be at approximately the rate as air is 25 drawn into the drain line at the bottom of the tub by operation of the blower unit 18. The provision of two thermostats 26A and 26B one near the top of the tub 10 and the other in the sump 21 assures that when either of these thermostats reaches a sufficiently high temperature, the heater 26 will be turned off. Such mechanism provides for a cutting out of the dryer heating element at the proper time corresponding with the rapid rise in temperature of the 30 air being ejected from the machine and adjacent the drying clothes. This increasing temperature will be experienced as the clothes reach the dry condition and this increase in temperature will result in shutting off the heating element 26.

40 Although the invention has been described by reference to a specific structure it is intended that various modifications may be made without departing from the fundamental principles herein disclosed and within the scope of the following 45 claims.

I claim:

1. In a washing and drying machine of the character described, a washing and drying chamber, a heating chamber adjacent said washing and drying chamber, a connecting passage between said heating chamber and said washing and drying chamber, overlapping louver members adapted to close said passage, mechanism to operate said louvers to open and close the passage 50 between said heating chamber and said washing and drying chamber, an outlet at the bottom of said washing and drying chamber, a fluid circulator connected with said outlet adapted to operate as a pump to carry liquid during operation 55 of the machine for washing and as a blower for exhausting air during operation of the machine for drying.

60 2. In a combined washing and drying machine of the character described, a washing and drying chamber, a heating chamber adjacent the upper portion of said washing and drying chamber, a connecting passage between said heating chamber and said washing and drying chamber, a closure for said passage, mechanism to operate 65 said closure to close said passage during washing and to open said passage during drying, a heating element in said heating chamber above said connecting passage, an air circulator above said heater to circulate air from said heating chamber over said heater and into said washing and dry- 70 75

ing chamber, an outlet near the bottom of said washing and drying chamber, a circulator connected with said outlet to act as a pump to carry liquid during operation of said machine for washing, mechanism to increase the speed of said circulator causing said circulator to act as a blower for exhausting air during operation of said machine for drying.

3. In a combined washing and drying machine of the character described, a washing and drying chamber, a heating chamber adjacent the upper portion of said washing and drying chamber, an inlet for said heating chamber, a connecting passage between said heating chamber and said washing and drying chamber, overlapping louver members adapted to close said passage during operation of said machine for washing, mechanism adapted to open said louver members during operation of said machine for drying, an outlet at the bottom of said washing and drying chamber, a fluid circulator connected with said outlet which serves as a water pump during the operation of the machine as a washer and as a blower to remove air during the operation of the machine as a dryer.

4. In a combination washer and dryer of the character described having a washing and drying

chamber, air heating and circulating means adjacent said chamber providing air circulation into the upper portion of said chamber, an outlet in the bottom of said chamber, a fluid and air circulator connected with said outlet serving as a pump for removing water during the operation of the machine as a washer, and mechanism to increase the speed of said circulator sufficiently to enable it to act as a fan for exhausting air during operation of said machine for drying.
